UNITED STATES PATENT OFFICE.

WILSON WORTH BURSON, OF ROCKFORD, ILLINOIS, ASSIGNOR TO B. Z. B. KNITTING CO., OF ROCKFORD, ILLINOIS, A CORPORATION OF ILLINOIS.

NEEDLE FOR KNITTING-MACHINES.

1,391,043.

Specification of Letters Patent. Patented Sept. 20, 1921.

Application filed August 4, 1917. Serial No. 184,408.

To all whom it may concern:

Be it known that I, WILSON W. BURSON, a citizen of the United States, residing in Rockford, in the county of Winnebago and 5 State of Illinois, have invented a new and useful Improvement in Needles for Knitting-Machines, of which the following is a specification.

This invention relates in general to 10 needles provided for knitting machines.

A principal object of the invention is to provide a needle for the foregoing and like uses of more certain and efficient operation than has been heretofore usual and at the 15 same time requiring less space on the cam carrying bar and thereby reducing the amount of space required by a single set of cams and enabling in some machines the use of a plurality of sets of cams in the place of 20 the one so that the machine may knit more than a single thread at each passage of the cam carrying bar.

A further object of the invention is to provide a needle which may be used in place of 25 the latch needle and may be made of smaller dimensions and consequently adapted for the knitting of finer yarn.

A still further object of the invention is the provision of a needle for knitting machines which may be cheaply constructed 30 and largely by punch and die work.

A still further object of the invention is the provision of a needle for accomplishing the foregoing and other objects, which 35 will keep the old and the new loops separated effectively and which will possess no tendency to catch in the yarn or other material being knitted.

A still further object of the invention is 40 the provision of a knitting needle of the character described, which will present a relatively small part for insertion within the loops and consequently permit the knitting of closely knitted goods.

45 Other objects and advantages of the invention will be apparent as it is better understood from the following description when considered in connection with the accompanying drawing illustrating a preferred embodiment thereof.

On the drawing,

Figure 1 is a side elevation of a knitting needle embodying my present invention with the needle bed shown in section and the knit-

ting needle extended to pick up the yarn for 55 a new loop;

Fig. 2 is a similar view showing arrangement of the parts as they near the completion of the knitting stroke;

Fig. 3 is a top plan view of the part 60 shown in Fig. 2;

Fig. 4 is a section on the line 4—4 of Fig. 2; and

Fig. 5 is a section on the line 5—5 of 65 Fig. 2.

The knitting needle shown on the drawing for the purposes of illustrating the embodiment of my present invention comprises a knitting hook member and a lifting hook member connected together by a pair of 70 rocking arms which, as the knitting hook member reciprocates, serve to engage the old loops and lift them up over and off of the knitting hook while it is carrying the new loops.

75 Reference character 11 indicates generally the knitting hook member and reference character 12 the lifting hook member. The lower edge 13 of the knitting hook member is preferably flat and slides back and forth 80 on the needle bed 14. This sliding is imparted by the needle jack 15, only a part of which is shown on the drawing, this jack having the usual engagement at 16 with the knitting hook arm or member at the rear 85 end. At the operative end the knitting hook proper 17 is provided, this hook consisting of an overturned lip as shown on the drawing. Rearwardly of the hook 17 the needle arm or member is substantially 90 straight providing an upper edge or surface 18 along which the loops may slide from forming to lifting position. At the rear end of this part a depression 19 is provided to receive the lifting hook and it will be observed that the lifting hook proper, which 95 is indicated at 21, seats in this recess so that the loop may slide over and above it without danger of catching in the hook end. The hook members are mounted one above the other— 100 that is to say, in the present embodiment of the invention the lifting hook member is disposed above the knitting hook member and the two are connected together by guides or rocking arms 22, one of which is located 105 on each side of the two. The guides or rocking arms are pivotally connected at 23 with the lifting hook member and at 24 with the

knitting hook member. The knitting hook member is provided with an upstanding lug 25 in which is located the pivotal connection 24 between the guides or rocking arms and the knitting hook. The lifting hook member preferably consists of a flat strip of suitable material having an upwardly projecting part 26 near its front end in which the pivotal connection 23 is located, and a downwardly extending part 27 which terminates in the hook 21. The parts 26 and 27 of the lifting hook member are preferably such that they form a recess 28 in which the lug 25 may move, the pivot 23 being preferably located normally behind the pivot 24.

The body 29 of the lifting hook member extends along the top of the knitting hook member and its rear end 31 is turned back and formed into a spring to engage the side walls 32 of the needle channel. The body 29 of the lifting hook member is provided with a recess 33, the ends of which form stops adapted for engagement by an upstanding stop 34 of the knitting hook member and extending into the recess 33.

Each pivotal connection 23 and 24 is formed of a rivet 35 which extends through an aperture 36 in the centrally connected part, this aperture having flaring ends in which the guides or rocking arms forming the outer parts of the pivotal connection are depressed, the ends of the rivet being riveted down and disposed wholly within the outer surfaces of the guides 22. These surfaces 35 may be made smooth, if desired, by grinding after the riveting. In order that the parts may have the desired easy relative movement the aperture for the rivets is formed in a central bearing 30, which is preferably of 40 length minutely greater than the thickness of the hook members. In the operation of the needle the knitting hook is projected to engage the yarn and on its return a knitting movement carries the yarn with it forming 45 the new loop 41. This loop slides back over the surface of the knitting hook when the knitting hook is again projected arriving against the downwardly extending part 27 of the lifting hook member after the lifting hook has passed under the yarn to form the 50 next successive loop. This position of the loop is indicated at 42 and for the purposes of explanation may now be called the old loop since a new loop 41 is in the process 55 of formation. On the next return or knitting stroke, the hook 17 carries the yarn back forming a new loop and the hook 21 is lifted by the movement of the guides or pivot arms up over and beyond the in- 60 turned end of the knitting hook so that a further rearward movement of the needle causes the old loop 42 to drop from the knitting needle and over the new loop 41 which has just been formed. The relative 65 movements of the hook members are deter-

mined in part by the rocking arms and in part by frictional engagement between the spring 31 and the side walls 32 of the needle channel, that is to say, the spring 31 holds the lifting hook member against longitudinal movement with the knitting hook member except when the stop 34 engages the ends of the slot 33 which occurs near the ends of the forward and knitting strokes. During the parts of the stroke between 75 these stop engagements the lifting hook member is swung about the spring as a fulcrum by the rocking arms or guides 22 lifting the old loop over the new and returning the lifting hook to receiving position. 80 The movements are so timed that the lifting hook is disposed in its slot at the time the needle hook reaches the end of its forward stroke and picks up the new yarn. As the knitting hook starts back on its knitting 85 stroke the lifting hook starts up since the stop 34 moves out of engagement with the forward end of the slot 33. The hooks are in the arrangement shown in Fig. 2 when this stop engages the rear end of the slot 90 and so engaged the two parts move together back to the end of the rear or knitting stroke. Upon starting upon the next forward stroke the stop 34 leaves the rear end of the slot and the lifting arm moves back 95 to its normal or inoperative position arriving at the position shown in Fig. 1 before the loop 42 slides over the recess 19.

It will be manifest from the foregoing that the parts are kept in accurate register 100 by the separate guide members provided and since the hook members are positioned between these guides they may be very small and thin since it is not necessary that any direct connection between them be provided. 105 It will also be manifest from the foregoing that the old loop is positively and accurately lifted over the new and without danger of catching the yarn or tangling the loops. The necessary sliding movement is 110 greatly reduced and the necessary cam throw consequently less so that more cams can be utilized in a given space on the cam body. The part of the needle thrust through the loops may be small and closely knitted 115 goods made therefore by this needle.

It is thought that the invention and many of its attendant advantages will be understood from the foregoing description, and it will be apparent that various changes may 120 be made in the form, construction and arrangement of the parts without departing from the spirit and scope of the invention or sacrificing all of its material advantages, the form hereinbefore described being 125 merely a preferred embodiment thereof.

I claim:

1. A needle for knitting machines, comprising a knitting hook and a lifting hook and a pivot arm connecting the two, said 130

- pivot arm lifting the lifting hook as the knitting hook moves on its knitting stroke to raise the old loop above and over the new.
2. A needle for knitting machines, comprising a knitting hook, a lifting hook, an arm pivotally connected to each of said hooks, and means for restraining movement of said lifting hook with said knitting hook to cause said lifting hook to be lifted by 10 said arm at a predetermined portion of the cycle of knitting operation.
3. A needle for knitting machines, comprising a lifting hook member and a knitting hook member of substantially the same thickness and mounted one above the other, and 15 movable guides near the hooks of said hook members for retaining said hook members in proper relation.
4. A needle for knitting machines, comprising a lifting hook member and a knitting hook member arranged one above the other, and guides located near the hooks of said hook members and pivoted to said members for retaining said hook members in proper 25 relation.
5. A needle for knitting machines, comprising a lifting hook member and a knitting hook member arranged one above the other, and guides pivoted to said hook members for 30 retaining said hook members in proper relation.
6. In a needle for knitting machines, a rivet pivotally connecting a central part to two outer parts, said central part being pro- 35 vided with an aperture with flaring ends and said outer parts being depressed into said flaring ends of said aperture, a rivet engaging said outer parts and a latch member pivoted on said central part.
7. A needle for knitting machines, comprising a knitting hook member and lifting hook member said knitting hook having a straight line reciprocation in knitting and said lifting hook member having a movement composed of two movements about 40 points located respectively one adjacent to the hook and the other remote therefrom.
8. A needle for knitting machines, comprising a lifting hook member and a knitting hook member of substantially the same 45 thickness and mounted one above the other, and guides secured to both said members and near the hook for retaining said hook members in proper relation.
9. In a needle for knitting machines, a central and two outer parts, said outer parts being pivotally connected to said central part, a pivot member located within said central part and engaging the inner faces of said outer parts and a rivet through said outer 50 parts and through said pivot member for holding said pivot member in place.

Signed in the presence of two subscribing witnesses.
